DESIGN FOR A DECK OF PLAYING CARDS

Maximilian C. Meyer, Brooklyn, N. Y.

Application July 26, 1944, Serial No. 114,567

Term of patent 14 years

(Cl. D34—13)

To all whom it may concern:

Be it known that I, Maximilian C. Meyer, a citizen of the United States, residing at Brooklyn, in the county of Kings and State of New York, have invented a new, original, and ornamental Design for a Deck of Playing Cards, of which the following is a specification, reference being had to the accompanying drawing forming part thereof.

Fig. 1 is a face view of one card of a deck of playing cards,

Fig. 2 is a face view of another card thereof, and

Fig. 3 is a face view of a third card thereof, showing my new design.

The complete deck consists of 27 cards, the pictorial representation of Figure 1 being on 13 of said cards, the pictorial representation of Figure 2 being on 1 card, and the pictorial representation of Figure 3 being on 13 cards.

The back of the cards is conventional.

I claim:

The ornamental design for a deck of playing cards, substantially as shown and described.

MAXIMILIAN C. MEYER.
